Primary Examiner — Barbara Fox*Assistant Examiner* — Lilyana Bekic*(74) Attorney, Agent, or Firm* — Oliff PLC(57) **CLAIM**

The ornamental design for a disposable tubeless insulin pump, as shown and described.

DESCRIPTION

FIG. 1 is a perspective view of a disposable tubeless insulin pump;

FIG. 2 is a front view thereof;

FIG. 3 is a top view thereof;

FIG. 4 is a right-side view thereof;

FIG. 5 is a left-side view thereof;

FIG. 6 is a rear view thereof; and,

FIG. 7 is a bottom view thereof.

The broken lines in the drawings illustrate portions of the disposable tubeless insulin pump that form no part of the claimed design.

1 Claim, 6 Drawing Sheets(56)
